INCLINOMETER

Emil Christensen, Portland, Oreg.

Application November 20, 1934, Serial No. 753,878

5 Claims. (Cl. 33—209)

My invention relates to devices for indicating rate of climb in an airplane or automobile in which the grade of the vehicle with respect to the horizontal is indicated by fluid in a transparent tube.

Broadly speaking such devices are old and many attempts have been made to construct a suitable instrument of this general character that would reliably and correctly indicate grade and rate of climb or descent.

While some of these various attempts have met a modicum of success the stumbling block has always been to damp the movement of the indicating fluid so that surges, shocks and abrupt changes would not produce such a violent movement of the indicating fluid as to render the device substantially useless.

The objects of my invention may be succinctly stated in their major features as follows:

20 An inclinometer of the character indicated with an efficient damping device that does not go into action on slight changes of grade but will positively damp the flow of fluid with abrupt changes or in the event of shocks so that the 25 reading may be relied upon.

Another object of my invention is a two fluid inclinometer of this type that will automatically readjust itself should the instrument be turned upside down or in any other manner be turned 30 from its normal position to such a degree that normal positions of the two fluids are disarranged.

A further object of my invention is an air chamber in connection with the fluid containing 35 tubes and so arranged that it will take care of the normal expansion and contraction of the fluids due to temperature changes but which will in no way influence the reading of the instrument.

Another object of my invention, which is considered among the most important ones, is a damping device for the purpose hereinbefore indicated and in which the kinetic energy developed by a surge in fluid in the instrument will be applied to some extent, at the same time, to both 45 ends of that column of fluid that serves for indicating grade.

These and other objects are attained by the structure illustrated in the accompanying drawings and described in the specification.

50 In the drawing:

Fig. I is a side view of the liquid containing portion of the instrument with one-half of the supporting casing removed and mounted in an adjustable mounting, adapting it in this case to

be mounted on a steering column as shown in Fig. II;

Figs. II and IV are details of the mounting of the instrument shown in Fig. I, drawn to a smaller scale;

Fig. III is an enlarged view of the interior of the upper part of Fig. I enlarged to clearly indicate its structure and mode of operation;

Fig. IV includes an enlarged view of the indicating part of the instrument;

Fig. V is the valve member 6 in plan;

Fig. VI is a longitudinal sectional elevation of the element 16 containing the valve 6 and showing construction for holding it in place;

Fig. VII is a top view of Fig. VI;

Fig. VIII is a broken away part of an orthographic projection of Fig. VI;

Fig. IX is a broken away part of an orthographic projection of the lower part of Fig. VI in proper position; and

Fig. X is a section on the line X—X of Fig. VI.

Referring to Fig. I, a generally triangular shaped fluid container 7, having a base portion 8, a transparent indicating side leg 20, a reservoir portion 10, and a central bisector tube 11, is 25 mounted in a two part casing 12, the two parts being held together by the bolt 13 and the wing nut 14, shown to be pivotally mounted on the arm 15.

The bisector tube 11, is arranged to contain the removable valve support 16, which is preferably a close fit within the bisector tube 11, and within which it will be cemented by a heat sensitive cement so that it may be removed on occasion without breaking the glass of which the whole 35 liquid containing part is preferably made.

The valve support 16, has an internal passageway 16a, within which is anchored a double acting surge valve member 6. This latter is preferably made of a thin wafer of steel having a 40 thickness of the order of thousandths of an inch. The valve 6 co-operates with the ports 6a, 6b, 6c, and 6d. A conventional way of supporting the valve 6 in position is indicated by the set screws 9.

The passageway 16a, is open to and in communication with the bisector tube 11, thence through the ports 6a, 6b, 6c, and 6d to the upper end of the fluid containing chamber.

The lower portion of the fluid container 7 is 50 partially filled with mercury as at 7a, upon which is superposed a lighter fluid, which may be glycerine thinned by alcohol, at 7b.

It will be noted that the reservoir portion 10 has greater volume than the remaining portions 55

of the fluid container and therefore in case of surges it will dominate the movement of fluid in the entire apparatus.

Considering the relative positions of the fluids shown in Fig. I and with the instrument at rest the mercury will be level in all of the several legs though it has not been shown level in the passageway 16a above the bisector tube 11 because that part is considered to be opaque and 10 an attempt to show it would be confusing.

The upper portion of the fluid container 7, contains a stopper 17, which is preferably a cork sealed in with sealing wax at 18. The cork 17 rests upon the top of the valve support 16, liquid 15 tight.

It will be noted that a gradual movement of incline of the instrument will not affect the valve 6, and the level of the mercury or indicating portion of the fluid will gradually change according to the level but should a surge occur the valve will immediately move to control the ports 6a, 6b, or 6c and 6d and shut them off in the direction of the surge. The passageway up through the bisector tube 11 and past the valve 6, however, remains open so that the surge influence, be it pressure or suction, will be felt at both ends of the index tube 20, though the force will be unbalanced to some extent. This constitutes the damping arrangement and as soon as 30 the indicating fluid in 20 moves slowly to its proper position, the valve 6 being resilient will resume its normal disengaged position as shown in Fig. I and the instrument will register the true grade. The valve 6 will move to close the 35 ports 6a and 6b if the surge is in one direction, or 6c and 6d if the surge is in the other direction.

The passageway 16a extends all the way around the valve 6 and is in open communication 40 with the bisector tube 11 and its purpose is to provide a restricted flow passageway when the surge valve has operated. Considering Fig. I, and assuming it to be moving at high speed toward the right. When very rapidly decelerated, the reed-like valve 6 will first close port 6c and afterwards 6d if the resultant surge is strong enough; this action is obvious from the angularity of the valve, which of necessity must be very flexible. See Fig. VI. The inertia of the liquid 45 in the several tubular parts to the right of the bisector tube 11 will be substantially balanced through the passage 16a; the top of the indicator tube will be momentarily sealed off by the valve 6; and motion of the fluid in the indicator 50 tube and that part of 7 to the left of the bisector 11, will be momentarily almost completely damped; thus deceleration will have little visible effect on the indicator tube.

In case of rapid acceleration the valve 6 closes 60 against the ports 6a and 6b in the same manner as heretofore described when the superior weight of the fluid in the reservoir portion will be felt at both ends of the indicator tube, also tending to neutralize the inertia effect.

It will be observed that by making the valve 6 after the schematic plan shown in the drawing, a surge movement in either direction will cause a movement of the valve to close the corresponding ports so that the valve is double acting. 65

This instrument constructed as shown is particularly suitable for airplane use. An airplane can be and frequently is flown upside down, and it will be noted that the several legs of the instrument connected across the top and at the 70

bottom and by the bisector tube 11 and the passageway 16a, form efficient equalizing means permitting the two fluids to resume their proper position and relationship immediately on the instrument assuming its proper position.

It will be noted that the space above the lighter fluid may be either a partial vacuum or may contain air at atmospheric pressure as of the temperature at which the tube was charged with fluid.

These chambers accommodate the thermal expansion of the fluids and the upper ports 6a and 6c control communication between the two air chambers, it being understood that the sides 16c and 16d are hermetically sealed to that portion 15 of the liquid container 7 with which they contact.

I am aware that two-fluid inclinometers have been attempted heretofore, that restrictions have been placed in passageways to act as dampers to 20 the movement of the fluid, but I am not aware that my bisector type has ever been used whereby surge influence will appear at both ends of the indicating column of fluid, nor is it apparent that a double acting valve of the character shown 25 and described here has ever been applied to an instrument of this character.

Having thus fully disclosed the principles governing the construction of my new inclinometer, what I claim as new and desire to secure by Letters Patent, is,—

1. A fluid type inclinometer defined in part as a triangular tubular element, comprising an indicator tube, an oppositely disposed tubular reservoir portion, a bisector tube, an apex forming communication means between the tops of the named members, said communication means being formed to provide oppositely disposed ports, and a double acting surge valve mounted for movement to control the ports under the influence 40 of surge of contained fluid.

2. The combination characterized in claim 1 and including an air chamber in the apex immediately above the ports.

3. A liquid type grade indicator, comprising an indicator tube, an oppositely disposed reservoir, normally open communication means between top and bottom of said members, said top communication means being formed to provide a plurality of pairs of oppositely disposed ports, a double acting surge valve mounted for movement to control said ports under the influence of fluid surge and a bisector tube to relieve the surge.

4. A liquid type grade indicator, comprising an indicator tube, an oppositely disposed reservoir, normally open communication means between top and bottom of said members, said top communication means being formed to provide a plurality of oppositely disposed ports, a double acting surge valve mounted for movement to control said ports under the influence of fluid surge and a normally open bisector tube within which said valve is operatively mounted.

5. A liquid type inclinometer defined in part as a bisected obtusely triangular tubular liquid container, comprising an indicating tube, an oppositely disposed reservoir tube, normally open apex communication means at the top of the reservoir and indicating tubes, an open base tube connecting the respective bottoms thereof, a bisector tubular member between said base and said apex and a double acting surge valve in said bisector that is arranged to control said apex communication under the influence of fluid surge.
